UNITED STATES PATENT OFFICE.

JOHN PETER OTTO MARQUART, OF CRESTLINE, OHIO.

BRUSH.

No. 893,635.

Specification of Letters Patent. Patented July 21, 1908.

Application filed January 6, 1908. Serial No. 409,432.

To all whom it may concern:

Be it known that I, JOHN PETER OTTO MARQUART, a citizen of the United States, residing at Crestline, in the county of Crawford and State of Ohio, have invented certain new and useful Improvements in Brushes, of which the following is a specification, reference being had to the accompanying drawings.

10 My invention relates to improvements in brushes and more particularly to brushes which are provided with a reservoir for the liquid to be applied by the brush; and an object of my invention is to provide a brush 15 of the character just described which will prove simple in construction, comparatively cheap in manufacture and most efficient in operation.

In the drawings illustrating the principle 20 of my invention and the best mode now known to me of applying that principle, Figure 1 is a central vertical section through my new brush; Fig. 2 is a section on line A—A of Fig. 1; Fig. 3 is a detail showing the 25 valve and the valve stem; Fig. 4 shows a modified form of my invention in which a bottle is used as a reservoir and handle; and Fig. 5 is a section on line B—B of Fig. 4.

The top of the handle *a* is provided with a 30 stopper *b* which closes the opening *c* through which the chamber *a'* may be filled and (if occasion should require,) emptied. In the base of the handle *a* is screwed a ring or collar *d* between which and the central cup-shaped distributing plug *e* are secured the 35 upper ends of the bristles *f*. The top of the distributing plug *e* serves as a valve-seat and is provided with openings *g* which are normally closed by the valve *h*. The latter is 40 provided with a valve-stem *i* the lower end of which is formed with a head *j* between which and the top of the plug *e* is interposed a conical coil-spring *k* which normally holds the valve *h* upon its seat. The valve *h* is 45 provided with a base-disk *m* of rubber or like material.

In using the brush, the head *j* of the valve-stem is pressed against the article to be coated with the dressing, paint or other liquid contained in the reservoir handle *a*;

and in this way the disk *m* is raised from the valve-seat against the pressure of the spring *k*, thereby allowing the liquid in the reservoir or chamber *a'* to flow through the holes *g* and to be distributed among the bristles *f*. 55

When the brush is not in use, the bristles are protected by the cover *n*.

In Figs. 4 and 5, a modified form of my invention is shown in which the brush is inserted in the mouth of a bottle *o*. A rubber band *p* encircles the collar or ferrule *q* and serves to seal the mouth of the bottle and prevent leakage of the contents thereof. The valve-stem *i* will serve as a guide along which the liquid will trickle and the same is 65 true of the coil-spring *k* and the cylindrical walls of the central plug *e*.

It is obvious that by unscrewing the ferrule or binding ring *d* from the base *m* of the reservoir handle *a*, the chamber *a'* may be 70 filled or emptied through that end.

My new device is particularly adapted for use in applying shoe dressings, liquid blacking and the like; but it is obvious that any liquid to be applied as a coating by the brush 75 may be used in the reservoir *a'*.

I claim:

1. The combination with a handle formed with a chamber and having an opening at one end, of a ring which extends into said opening and is provided with means for maintaining it therein; a central cup-shaped distributing plug the base of which is perforated and extends into said chamber; a valve which is normally seated directly upon the base of 80 said plug and closes the holes therein; a valve-stem for said valve; a coil spring one end of which bears against the base of said plug and the other end of which presses against an end of said valve-stem; and bristles the inner ends of which are held firmly between said ring and plug.

2. The combination with a handle formed with a chamber and having an opening at one end, of a ring which extends into said opening; a central cup-shaped distributing plug the base of which is perforated and extends into said chamber; a valve which is normally seated directly upon the base of 95 said plug and closes the holes therein; a 100

valve-stem for said valve; a coil spring one end of which bears against the base of said plug and the other end of which presses against an end of said valve-stem; bristles 5 the inner ends of which are held firmly between said ring and plug; and a sealing ring which encircles the first-named ring and seals the joint between the first-named ring and the walls of said opening.

In witness whereof I have hereunto set my hand at said Crestline this 28th day of December, 1907, in the presence of the two undersigned witnesses.

JOHN PETER OTTO MARQUART.
